UNITED STATES PATENT OFFICE.

EDWARD WILLIAM MACKENZIE HUGHES, OF CHICAGO, ILLINOIS, ASSIGNOR
TO THE FOX SOLID PRESSED STEEL COMPANY, OF SAME PLACE.

TRUCK.

SPECIFICATION forming part of Letters Patent No. 408,034, dated July 30, 1889.

Application filed June 11, 1889. Serial No. 313,911. (No model.)

To all whom it may concern:

Be it known that I, EDWARD WILLIAM MACKENZIE HUGHES, of Chicago, Cook county, Illinois, have invented a new and useful Improvement 5 in Trucks, of which the following is a full, true, and exact description, reference being had to the accompanying drawings.

This invention relates to an improvement in trucks, in which the side frames, end frames, and transom are formed of one piece of metal—by preference of pressed steel.

My invention will be readily understood from the accompanying drawings, in which—

Figure 1 represents an isometrical perspective; Fig. 2, a section through the transom C; Fig. 3, a bottom view of the transom, showing the supporting-plate; Fig. 4, an isometrical perspective showing the safety-bars for the axles; and Fig. 5, a longitudinal transverse section through the transom and center bearing-plate, showing the pressed-steel axle safety-bars in position.

My truck-frame itself consists of the side frames A, end frames B, and transom C, all pressed or shaped from one piece of metal, and preferably of box shape, as indicated. The center plate D may be pressed from the transom C or otherwise attached, as desired. The frame is made by cutting a suitable blank of 25 metal, preferably of steel, and pressing the same between dies in the manner now well known. The pedestals F may be simultaneously pressed, if desired. The axle safety-bars G are made of pressed-steel boxes, as 30 shown, and are supported on the end frames B by straps H, riveted or otherwise fastened to the axle safety-bars and the end frames, as

shown in Figs. 4 and 5. These axle safety-bars may be provided with wooden bearings K, to support the axle in case of breaking, in 40 the well-known way. The advantages of this truck are obvious, combining as it does the greatest strength, simplicity, and lightness.

Though I prefer to make my truck of pressed steel, other metals may be used. The transom C is preferably supported by the stiffening-plate D, which may be riveted to the sides of the transom C and to the side frames A, as clearly shown in Figs. 1 and 3.

What I claim as my invention, and desire 50 to secure by Letters Patent, is—

1. A truck-frame for rolling vehicles, in which the side frames, end frames, and transom are formed of one piece of metal, substantially as described.

2. A truck for rolling vehicles, having the side frames, end frames, and transom all pressed of one piece of metal so as to form boxes, substantially as described.

3. The combination of the truck A, with 60 the axle safety-bars G, formed of pressed steel, substantially as described.

4. The truck for vehicles herein shown, having the side frames, end frames, and transom and pedestals all pressed from one piece of 65 metal, substantially as described.

In testimony whereof I have signed my name to this specification in the presence of two subscribing witnesses.

EDWARD WILLIAM MACKENZIE HUGHES.

Witnesses:

W. S. HARTWELL,
W. M. VOSS.
